UNITED STATES PATENT OFFICE.

THOMAS BENTON SMITH, OF NASHVILLE, TENNESSEE.

IMPROVEMENT IN LOCOMOTIVES.

Specification forming part of Letters Patent No. 154,289, dated August 18, 1874; application filed June 20, 1874.

To all whom it may concern:

Be it known that I, THOMAS BENTON SMITH, of Nashville, in the county of Davidson and State of Tennessee, have invented a new and useful Improvement in Device for Increasing the Traction-Power of Locomotives, of which the following is a specification:

Figure 1 is a side view of a locomotive and tender to which my improvement has been applied. Fig. 2 is a top view of the same. Fig. 3 is a detail cross-section of the same, taken through the line x x , Fig. 1.

Similar letters of reference indicate corresponding parts.

My invention has for its object to prevent the drive-wheels of a locomotive from slipping upon the rails by using the weight of the train being drawn to give a downward pressure upon the drive-wheels, causing them to hug the rails, thus increasing the traction-power of the locomotive, and enabling it to draw a train of cars up a steeper grade than would otherwise be possible.

The invention consists in the combination of the pivoted bars, the cross-bar, the draw-bar, the upright bars, the upper cross-bar, the piston-rod and piston, the steam-cylinder, and the three-way cock with a locomotive, as hereinafter fully described.

A represents a locomotive, and B a tender, which are constructed and coupled together in the ordinary way. C are two bars, the forward ends of which are pivoted to the opposite sides of the forward end of the locomotive A, and to the rear ends of which are pivoted the forward ends of the two bars D. The rear ends of the bars D, between the locomotive A and tender B, are connected by a cross-bar, F. With the middle part of the cross-bar F is connected the forward end of the bar E, which passes back through guides attached to the bottom of the tender B, and to its rear end is coupled the forward car of

the train. In the forward end of the draw-bar E is formed a slot, e', to receive the cross-bar F and give the necessary play to the coupling. To the bars C D, at their points of meeting, are pivoted the lower ends of two upright bars, G, the upper ends of which are connected with the ends of a cross-bar, H, the center of which is attached to the upper end of the piston-rod I, the piston J of which works in a steam-cylinder, K, attached to the locomotive A near the steam-dome M. The lower part of the cylinder K is connected with the dome M by a three-way cock, L, so that the steam may be admitted to the cylinder K below the piston J, and allowed to escape, when desired.

With this construction, when necessary, the engineer turns the three-way cock L and admits steam into the cylinder K, which forces the piston J upward, drawing the bars C D upward into the angular position shown in dotted lines in Fig. 1. With this arrangement the weight of the train tends to draw the bars C D downward into a horizontal position, which throws the weight of the train upon the drive-wheels of the locomotive, causing them to hug the rails, and thus greatly increase the traction-power of the locomotive.

Having thus described my invention, I claim as new and desire to secure by Letters Patent—

The combination of the pivoted bars C D, the cross-bar F, the draw-bar E, the upright bars G, the cross-bar H, the piston-rod and piston I J, the steam-cylinder K and the three-way cock L with a locomotive, A, substantially as herein shown and described, and for the purpose set forth.

THOMAS BENTON SMITH.
